ABSTRACT: An air valve is disposed in the air flowing through a carburetor to the intake manifold of an internal combustion engine. A fuel valve controls the fuel flow to a mixing chamber which produces a suspension of fuel particles which are entrained in the airflow. The air valve is operably connected to the fuel valve through the mixing chamber.

FUEL-CONTROLLING DEVICE

BACKGROUND OF THE INVENTION

1. Field of the Invention

This invention pertains to the field of carburetors for an internal combustion engine in which the airflow into the intake manifold is used to control the flow of fuel to a mixing chamber.

2. Prior Art

It is well known that an internal combustion engine provides maximum power output when the airflow into the intake manifold is at maximum and there is a correct proportion of fuel to air. At any running condition of the engine the ultimate power is decreased if the airflow is less than that demanded by the engine.

Carburetors have been used which include air valves for sensing the airflow and controlling a fuel valve for metering the amount of gas flow into the fuel-air mixing chamber. In the mixing chamber air is mixed with fuel to provide suspension fuel particles which are entrained into the airflow and then into the intake manifold of the engine. In such prior carburetors the air valve has been mechanically connected to the fuel metering valve by rigid rods which were journaled in apertures made in the carburetor housing. When the power or speed of the engine changed, these rods moved within the journal and thereby has developed frictional impairment of free axial movement of the rods thereby hampering the correct free response of the gas valve to airflow. On the other hand if the journals are enlarged to minimize friction, fuel in the form of vapor fuel particles would escape through the enlarged journals in the float chamber to the mixing chamber. This escaping fuel would bypass the fuel-metering pin and seat which controls the air-fuel ratio thereby varying the ratio from a desired value.

Another problem with prior carburetors has been in providing proper damping of the air valve. Without damping, upon change in engine demand for air the air valve would bounce or oscillate above and below the stable or balance position for a substantial period of time which resulted in inefficient operation. It has been known to use a damper plate immersed within fuel as the damping medium in order to quickly damp out the oscillation. However, if the damping factor is too high, a long period of time may be required before the balance position is reached. This will increase the lag of time between applying on or off the accelerator and the response by the engine to increase or decrease power. Such time lag has an adverse effect on the performance of the automobile and in the safety of the operation. Accordingly, prior carburetors have a lot to be desired in providing an optimum damping factor where the stable position is reached in as short a period of time as possible.

BRIEF OF SUMMARY OF THE INVENTION

In accordance with the invention there is provided a carburetor for an internal combustion engine having a housing with an air intake opening and an output opening. Air flows from the intake opening to the output opening. Fuel and air are mixed in a mixing chamber which produces a suspension of fuel particles in air which are entrained in the airflow. A fuel valve communicates with a fuel source and is operable to control the flow of fuel to the mixing chamber. An air valve is disposed in the airflow and is movable in accordance with the flow from the intake to the output opening. The air valve is operably connected to the fuel valve through a coupling which passes through the mixing chamber. In this manner there is reduced the undesirable friction forces of connectors journaled in the carburetor housing.

Further in accordance with the invention the carburetor includes a damper member disposed within a damper housing. The damper member is operably coupled to the fuel valve. The flow between the damper housing and the source of fuel is selectively varied to provide a variable damping factor. In this manner an optimum damping factor may be achieved.

BRIEF DESCRIPTION OF THE DRAWINGS

FIG. 1 is a sectional view of a carburetor of the present inventive concept taken along the section line 1-1 of FIG. 2.

5 FIG. 2 is a sectional view of the carburetor of FIG. 1 taken along the section line 2-2 of FIG. 1.

FIG. 3 is a sectional view of the portion of the carburetor of FIG. 1 taken along section line 3-3 of FIG. 1.

10 FIG. 3A is a modification of the invention of FIG. 1 in which a swirl action is produced.

FIGS. 4 and 5 is an exploded perspective view of the air valve, fuel metering and damping system of FIG. 1.

15 FIG. 6 is a further modification of FIG. 1 in which a floatless chamber is used.

DETAILED DESCRIPTION OF THE DRAWINGS

FIGS. 1-3 show a hollow carburetor housing indicated generally by numeral 10 having an air intake opening 11 and a second mixing chamber 12 which is in communication with a conventional intake manifold (not shown) of an internal combustion engine.

20 As the engine operates it will produce suction at chamber 12 and therefore air flows into the air intake 11 past a conventional choke valve 14 through chamber 12 and into the intake manifold. An air valve 15 is disposed in the airflow within chamber 12 and as the engine demands more air the air valve 25 senses the weight rate of airflow and moves upwardly. A portion of the airflow passes through the inner opening of valve 15 and the remainder passes between valve 15 and the inner wall of chamber 12.

VALVE 15—ROD 30—PIN 34

30 In the static rest position the annular body 16 of air valve 15 is supported by a valve seat 17 which is adjustably secured by a lock screw 17c to a hollow stem 20 having an enlarged ring-shaped bottom portion 20a. The bottom portion 20a is engaged in an annular shoulder 21 of housing 10 formed at the upper edge of chamber 22 containing fuel.

40 Air valve 15 includes a spider defined by four straight vertical ribs 15a-d extending inwardly from body 16 with the ribs meeting to form a hollow cylinder 15e. Secured within cylinder 15e is a sleeve 24 having a washer-shaped upper member 24a and a lower portion which may be peened under cylinder 15e. Upper member 24a has four openings in which there are secured respectively the lower ends of rods 25a-d. The upper ends of rods 25a-d are secured within openings 28a-d. The upper ends of rods 25a-d are secured within 45 openings 28a-d respectively of a pin holder 28. Rods 25a-d may be secured to the respective openings of member 24a and holder 28 by welding, as for example. A center opening 28e of pin holder 28 threadedly engages the upper end of a pin rod 30 which extends through without touching a tube 32 and the inner chambers of hollow stem 20. Rod 30 at its lower end, is secured in an opening in an upper end of a fuel valve metering pin 34, the lower end of which is connected to a damper plate 36. Accordingly, metering pin 34 and damper plate 36 move 50 upwardly and downwardly as air valve 15 is urged upwardly and downwardly respectively by the airflow through chamber 12.

55 Metering pin 34 is tapered so that as it travels in an upward direction the annular clearing between pin 34 and a valve seat 37 threadedly engaged within hollow stem 20, increases in area. In this manner a greater amount of fuel within chamber 22 is allowed to flow into a first mixing chamber 39 formed within stem 20 adjacent to the upper end thereof.

60 The supply of air for mixing chamber 39 is taken from below valve seat 17 by way of air passages 40. Tube 32 extends upwardly from chamber 39 into chamber 12. In order to provide suction in chamber 39, a pressure difference is 65 produced between the upper and lower sides of air valve 15 which is effective to suck up the mixture of suspension of fuel particles in the air through tube 32. Accordingly, the mixture is directed out of the upper end of the tube and into the

air which flows through second mixing chamber 12 outside of tube 32.

It will now be understood that the only mechanical coupling between air valve 15 and metering pin 34 includes a supporting structure of rods 25a-d and holder 28 and an elongated member or rod 30. Rod 30 extends downwardly through tube 32 and through hollow stem 20 which includes first mixing chamber 39. Accordingly, there is avoided the use of friction producing members which have in the prior art been journaled in apertures in the carburetor housing for coupling the air valve with the metering pin and the damper plate. Alternatively, there is eliminated the amount of fuel which would escape through enlarged journals from the fuel chamber to the mixing chamber bypassing the metering device.

AIR VALVE 15

Inner Opening

Annular body 16 has an inner wall 16a which forms an inner central opening of air valve 15. Wall 16a defines a downwardly and outwardly rounded surface. An annular beveled surface 17a of seat 17 smoothly mates with inner wall 16a when valve 15 is in the static rest position. As air valve 15 moves upwardly, a straight-through smooth streamlined profile for airflow is provided through the inner opening of valve 15 and between seat 17 and valve 15. This streamlined profile is particularly important when valve 15 and seat 17 are substantially close to each other forming a sharp corner to airflow as for example during idle and at low cruise speeds. A sharp corner or nonstreamline profile provides substantially more resistance to airflow than a smooth streamline profile. Thus the major portion of air flowing through the inner opening flow with less resistance as compared with a nonstreamline profile. It will be understood that the boundary layer of air on and adjacent to the inside wall of chamber 12 will be increased in thickness as compared with a nonstreamline profile. Thus the velocity of the air on or adjacent the inside wall is decreased.

Outer Wall

Body 16 has an outer wall 16b adjacent to which inner wall 12a of chamber 12 is inclined in an upwardly and outwardly direction in a manner well known by those skilled in the art. As air valve 15 moves upwardly, the clearing for airflow between outer wall 16b and inner wall 12a increases in area when the lower edge of wall 16b passes the beginning 12b of inclined walls 12a. Accordingly, with valve seat 17 secured to stem 20 by lock screw 17c in the position illustrated, valve 15 travels a substantial distance in response to a minimum demand for air by the engine. At idle speed the engine demands a minimum amount of air and valve 15 is required to travel upwardly until the lower edge of wall 16b passes the beginning 12b of the incline and until the minimum demand for air is satisfied. It will be understood that after the lower edge passes the incline beginning 12b, the air demand is controlled by the slope of the incline. This travel, of substantially a high order of magnitude, is transmitted to pin 34 thereby providing a substantially large area clearing at idle. On the other hand, if valve seat 17 is secured to stem 20 at a position above that illustrated, valve 15 is required to travel upwardly a lower order of magnitude to meet the engine minimum demand for air flow at idle. Accordingly, at idle speed the annular clearing between pin 34 and seat 37 is of substantially less area than in the previous position of seat 17. In this manner, by varying the position of seat 17 the travel of valve 15 may be adjusted to control the fuel air ratio at idle.

Travel Control Leaves

The travel of air valve 15 may also be controlled by adjusting the position of travel control plates or leaves 42a-d, with each of the leaves defining a segment of a flat washer. A slot is formed in each of the leaves 42a-d to receive a screw which is threadedly engaged in an opening formed in the upper surface 16c of body 16. In this manner leaves 42a-d may be adjusted and then rigidly secured in position to determine the effective inside diameter of the central opening of air valve 15.

Guides

In order to guide the movement of air valve 15 there are provided three downwardly extending projections 18a-c from annular body 16. Projections 18a-c include downwardly extending keyways 19a-c respectively for receiving respective guide pins 23a-c secured in chamber 12. In addition a longitudinal keyway 17d is formed in the cylindrical inner wall of seat 17 for receiving a longitudinal key 17e formed on the outer surface of stem 20.

IDLE ADJUST

The fuel-air ratio at idle may be finely adjusted by raising or lowering metering pin 34 while valve 15 is in a static rest position in the following manner. Metering pin 34 is fixedly secured to damper plate 36 which has a notch guide 36a. Guide 36a is engaged by a vertical pin 45 secured to the vertically extending cylinder wall of a cylindrical damper housing 46 surrounding plate 36. The lower end of damper housing 46 is closed and there extends downwardly from the closed end a screwhead 46a which may be turned from the outside of carburetor 10 by inserting a screwdriver in head 46a. Accordingly, by manually turning screwhead 46a, housing 46 is rotated thereby rotating damper plate 36, metering pin 34 and rod 30. Accordingly, as damper plate 36 is rotated the upper end of rod 30 is screwed into or out of threaded opening 28e of holder 28. In this manner metering pin 34 may be raised or lowered with respect to valve seat 37 while valve 15 is in the same static rest position.

VARIABLE DAMPING

Damping of air valve 15 is provided by fuel acting as a damping medium on damper plate 36. As valve 15 and plate 36 go lower, fuel is forced out of the volume of fuel between plate 36 and the lower closed end of housing 46. This fuel flows out through the relatively small clearing 36a forming a fluid connection between the edge of plate 36 and the inner wall of housing 46 into the remaining fuel in chamber 22. Similarly, as valve 15 and plate 37 are raised, fuel flows from chamber 22 through the fluid connection into the space between plate 36 and the closed end of housing 46. It will be understood that this fluid connection is of constant cross-sectional area thereby producing a constant damping factor. In order to provide a variable damping factor, the fluid connection is effectively varied in cross-sectional area thereby to vary the flow of fuel in the following manner.

As best shown in FIGS. 4 and 5, a plurality of equally spaced openings 47 are formed around a circumference of housing 46 adjacent to the lower closed end. A damper control cylinder 50 having a lower closed end 50a receives damper housing 46 with screwhead 46a extending through a central opening in end 50a. An annular shaped shoulder extends horizontally from the lower closed end 50a and has formed therein semicircular slots 50b-c. Screws 51a-b extend through respective slots 50b-c and engage threaded openings on the underside of a bottom base 56. Base 56 is fixedly secured to the bottom edge of housing 10 as for example by screws. It will be understood that base 56 may be an integral part of housing 10. Cylinder 50 may be rotated about its axis by first loosening screws 51a-b and then inserting a spanner wrench in the openings provided. Screws 51a-b are then tightened.

The vertically extending cylindrical wall of cylinder 50 may be about half the height of the wall of housing 46 with an O-ring seal 52 being disposed in sealing relation between the two walls. Below O-ring seal 52 and adjacent openings 57 there are provided in the wall of control cylinder 50 two opposed elongated rectangular openings 54a-b. Base 56 includes a vertically extending cylindrically shaped wall 57 which extends above openings 54a-b. Opposing sections of wall 57 are beveled to form 57a-b. Lines drawn from the ends of sections 57a-b to the centerline of base 56 form angles which may be approximately the same as angles formed by lines drawn from the ends of openings 54a-b to the center of cylinder 50. It will now be understood that an adjustable fluid connection may be

ed from the fuel in housing 46 below plate 36 throughings 47 leading to openings 54a and 54b, through beveled ions 57a, 57b, to the fuel within chamber 22. The forego-
adjustable fluid connections are in parallel with each other
with the constant fluid connection through the side of
36 to provide a resultant adjustable fluid connection.

order to adjust the damping, cylinder 50 may be rotated
it its axis in the manner previously described so that
ings 54a-b are substantially in line with sections 57a-b
ctively. In this way there is provided a resultant fluid con-
ion of maximum cross-sectional area thereby to produce
mum damping. On the other hand, cylinder 50 may be
ed so that openings 54a-b are completely covered by ver-
nonbeveled walls 57 so that the resultant fluid connection
minimum cross-sectional area thereby providing max-
n damping. It will be understood that damper control
der 50 may be turned to positions between the foregoing
one minimum and maximum damping positions to adjust
amping to an optimum level.

FLOAT CHAMBER 62—FUEL CHAMBER 22

el is supplied to chamber 22 from a float chamber 62
aining a float 65 by way of fluid connection or pipe 60.
60 has an outlet in chamber 22 adjacent the bottom
of and an intake opening 60a in chamber 62 which is
ed in the center of the projected horizontal area of
ber 62. At best shown in FIG. 2 the horizontal projected
of chamber 62 defines a shaped section having curved
s 62a-b and straight edges 62c-d parallel to each other.
e 60a to be in the center of the projected area is disposed
r to edge 62a than edge 62b and equidistant between
lel edges 62c-d.

locating intake 60a in the center of the area, it will be un-
ood that when the automobile carrying carburetor 10
the head of fuel at intake 60a is maintained constant. For
ipole, the automobile tips to the right thereby lowering the
end and raising the left end of housing 10. Thus, in
ber 62 the fuel is deeper in the right-hand end than in the
land end, but the center of chamber 62 remains constant
th for a constant head. This constant head is maintained
e automobile tips in any direction. In this manner there is
ed constant static fluid pressure at intake 60a.

e fuel in chamber 22 may not change in depth since the
e chamber is substantially filled with fuel as a result of the
evel in float chamber 62 being maintained above the top
amber 22. Accordingly, with a constant static fluid pres-
at intake 60a, the static fluid pressure is maintained con-
in chamber 22. Accordingly, the fuel feed to metering
4 is a function only of the suction produced in mixing
ber 39 and is not dependent on a varying fluid pressure.
is manner more accurate control of the air-fuel mixture is
ned, and therefore there is no cutoff or surge due to the
ng of the carburetor. With a separate float chamber 62
fuel chamber 22 containing damper plate 36, there is al-
d independent movement of float 65 and plate 36.
cifically, when damper plate 36 rises, it is because the en-
requires more fuel from chamber 22 and therefore float
ay lower to allow more fuel to flow into chamber 62. If
s two actions occur at the same time in the same
ber, as in the prior art, the damper plate prevents the
from swinging freely to feed in fuel. Therefore, an un-
y fuel flow results which causes a hesitation of the engine
rmance. This hesitation is caused since the flow of fuel
the chamber is in a direction opposite that of damper

36. Accordingly, by separating float chamber 62 from
ber 22, there is provided flexibility in allowing the float
he plate to move without producing interfering actions.
at 65 floats on the surface of the fuel in chamber 62 and
ecured thereto the lower end of a float arm 66 which
es about a pivot 68 and engages the left-hand end of a
needle 70. When float 65 is at a lower position indicating
fuel is required in chamber 62 the upper end of arm 66

moves to the left, thereby allowing fuel under pressure in inlet
73 to push open valve needle 70 from valve seat 72 and to flow
into chamber 62. When float 65 reaches its upper limiting
level, the upper end of arm 66 pushes needle 70 to the right
against valve seat 72 thereby preventing fuel from flowing into
chamber 62. The foregoing float and valving arrangement is
adjusted so that the lower fuel level is higher than the top of
chamber 22 for the reason previously described. In addition
inlet 60a is substantially below the lower fuel level in chamber
62 to assure that no foaming fuel passes into chamber 22.

It will be understood by those skilled in the art that suitable
O-ring seals may be provided in sealing relation between cover
56 and chamber 22 and between cylinder 50 and cover 56.

Float chamber 62 illustrated in FIGS. 1 and 2 may be
15 replaced by a floatless constant level chamber 80 as shown in
FIG. 6. Carburetors without floats are known in the art and
have the advantage of avoiding the use of a float. When a float
is damaged for example the carburetor floods and fuel may
20 escape from the carburetor onto the hot manifold causing a
fire.

However in prior floatless carburetors the overflow outlet
has been connected to the side of a single chamber containing
the float and the fuel chamber. Such a single chamber had the
disadvantages described above. As illustrated in FIG. 6 a
25 separate floatless chamber 80 is provided for supplying fuel to
chamber 22. As in the carburetor of FIGS. 1-5, tube 60 has
an outlet in chamber 22 and an intake opening 60a located in
the center of the projected horizontal area of chamber 80. A
30 constant flow of fuel enters by way of inlet 82 from a fuel
pump (not shown). In this manner fuel fills chamber 80 until it
reaches the level of an overflow outlet opening 84 of a tube
85. The overflow fuel flows into opening 84 through overflow
35 tube 85 back to the fuel tank (not shown). Tube 85 extends
through a lower opening 88 of chamber 80 and is secured in
place by a squeeze fitting 90 threadedly engaged in flange 88a.
A gasket is disposed in sealing relation between fitting 90 and
opening 88. To change the fuel level tube 85 may be moved
40 upwardly or downwardly by loosening fitting 90 and adjusting
tube 85. Opening 84 is always maintained above intake opening
60a.

Outlet opening 84 is located in the center of the projected
horizontal area of chamber 80. Thus, as the automobile tips
the fuel becomes deeper at one end of chamber 80 with
respect to the other end but the center of the area is main-
tained at a constant depth without the use of a float. Ac-
cordingly, the amount of fuel in chamber 80 is maintained
constant. As previously described with intake 60a in the
50 center of the projected horizontal area, as the automobile tips
a constant head is maintained on opening 60a. In this manner
the static fluid pressure is maintained constant in chamber 22
and the fuel feed to metering pin 34 is a function only of the
55 suction produced in mixing chamber 39. Now that the prin-
ciples of the invention have been explained, it will be un-
derstood that many more modifications may be made. For ex-
ample, the four straight ribs 15a-d forming a spider as shown
60 in FIGS. 1-4 may be twisted at a slight angle from the vertical
center line of each rib as illustrated in FIG. 3A. Thus, ribs
15e-h form a slight spiral and these ribs guide the airflow
through the inner opening of air valve 15 to produce a small
65 swirl action in the fluid motion in chamber 12. This swirling
action in conjunction with the thick boundary layer of air ad-
jacent the inner wall causes the heavier fuel particles in
chamber 12 to drop downwardly to be broken into small par-
ticles when they meet the fresh air entering from intake 11.
Thus there is provided an improved screen for fuel particles.

I claim:

1. A carburetor for an internal combustion engine comprising
a housing having an air intake opening and an output
opening,
2. a chamber in said housing for mixing said air with fuel
thereby to produce a suspension of fuel particles in air,
3. fuel valve means communicating with fuel in a chamber
for controlling the flow of fuel to said mixing chamber,

- d. a float chamber for supplying fuel to said fuel chamber,
- e. a fluid coupling for flow of fuel having an inlet in said float chamber and an outlet in said fuel chamber, said inlet being disposed in said float chamber to provide a constant static fluid pressure in said fuel chamber,
- f. air valve means moveable in accordance with the airflow from the said intake to said output opening, said air valve means having an inner opening for said air flow, and

5

g. adjustable means for selectively varying the effective area of said inner opening of said air valve means, said adjustable means comprising substantially horizontal travel control plates adjustably secured to said air valve means for movement radially to the axis of said air valve means for selectively varying said effective area of said inner opening
